UNITED STATES PATENT OFFICE.

EMIL A. HIRNER, OF ALLENTOWN, PENNSYLVANIA.

MANUFACTURE OF HOSIERY.

Application filed June 22, 1921, Serial No. 479,603. Renewed January 12, 1925.

My invention relates generally to the manufacture of hosiery, and more especially to a novel process of manufacturing seamless hosiery, and also to the product made 5 in accordance therewith.

In the manufacture of seamless hosiery as ordinarily practiced, the heel of the stocking is knit by narrowing and widening upon a limited number of fashioning needles 10 which results in the production of a pocket having, at each side, the diagonal sutures characteristic of such hosiery. The contour of the pocket produced under this method is at best but an approximation, and not only 15 lacks the necessary fullness, but falls far short of conforming accurately to the human heel. Moreover, difficulty has been experienced in preventing unsightly puckering of the heel pocket even after pressing, this being due to crowding of the fabric loops at 20 opposite sides of the diagonal sutures in endeavoring to adjust themselves compensatively with respect to the stretched loops which fall within the rounded portion of the heel beyond the outer ends of said sutures. 25

The purpose of my invention is to overcome the various objections, above pointed out, by enabling production of not only a rounder and fuller heel than heretofore possible with methods commonly in use, but one devoid of fashioning sutures within its area; so that the fabric loops constituting the 30 same are absolutely free from tension or restraint and as elastic as in any other portion 35 of the stocking.

Other objects and attendant advantages of my invention will become apparent from the detailed description which follows:

The figure of the drawing represents, more 40 or less diagrammatically, a stocking conveniently embodying my invention. Although illustrated as applied to half hose, my invention is equally applicable to seamless long hose or even to children's stockings 45 as will be obvious from subsequent disclosure.

In carrying out my invention, the leg portion of the stocking indicated at 1 is knit in the usual manner by round and round knitting upon a circular knitting machine. Upon 50 reaching the course represented by the line 2-3-4-5, rotation of the machine is suspended, and formation of the heel pocket begun by a fastening operation upon a limited series of needles. At this juncture, instead of producing the heel pocket by narrowing and widening as is generally cus- 55

tomary; I make a radical departure from the usual practice by beginning conversely, i. e., by widening, and form the heel in its entirety as a widening web. The method of procedure is as follows:

As an illustrative example let it be assumed, that the stocking herein shown is knit on a cylinder of two hundred and twenty-eight needles. Of these, I employ 60 half or one hundred and fourteen units as instep needles, which, during the formation of the heel, are rendered inactive to hold the loops of the fabric along the line 2-3 and also the corresponding loops on the other 65 side of the stocking. The remaining needles, with the exception of about twenty at the very centre of this series, I employ as fashioning needles, the latter being thus 70 divided into two groups of forty-seven each. At the beginning of the oscillation of the machine, the fashioning needles are as a body, rendered inactive, and, as the knitting proceeds, are added alternately, one at a 75 time, to opposite ends of the subdivision of twenty needles above referred to until the full complement is restored to activity. In this way, I produce the entire heel, or, in other words, the pocketed web ending at the line 3-6. The sutures 3-4 incidentally 80 formed through this operation, it will be observed, instead of extending diagonally of the heel, in a manner common to seamless hosiery as ordinarily manufactured, are coincident with what may be conveniently termed 85 the longitudinal median lines at opposite sides of the stocking foot, or in other words lie in the line of juncture between the heel and ankle, and, as a result, round upwardly 90 at their outer ends into the ankle of the 95 stocking as shown. At the conclusion of the widening operation just described, the loops of the fabric are held by the needles substantially along the line 2-3-6, and thereupon, the needle cylinder is again rotated and the foot 10 otherwise completed in the usual manner.

A stocking made in accordance with the above is entirely devoid of any puckering at the heel, and moreover by reason of the 100 fullness of the heel pocket and the characteristic disposal of the fashioning sutures peculiar to my invention, said heel is rendered just as elastic as any other portion of the stocking thus insuring perfect fit and 105 comfort to the wearer. A further distinctive characteristic may be noted in that as a con-

sequence of my improved method of knitting, the wales of the heel are directly continuous with those of the stocking sole with the advantage that the foot is more elastic lengthwise than in stockings manufactured in the ordinary way.

It is to be understood that the numerical proportions herein suggested, by way of example, in connection with the subdivision 10 of the knitting needles are subject to infinite variation in practice.

Having thus described my invention, I claim:

1. In the manufacture of seamless hosiery, 15 the process of producing the heel pocket which consists in knitting on a limited series of needles less than one-half of the full complement, gradually widening until one-half of the needles are in use, and then immediately beginning the foot portion by circular knitting on the full complement of needles.

2. In a seamless stocking, a heel pocket comprising a substantially triangular web having its apex merged into the leg portion 25 and its base coinciding with the first circular course of the foot portion.

3. In the manufacture of seamless hosiery, 30 the process of producing the heel pocket by commencing oscillatory knitting with a limited series of needles, gradually increasing the latitude of said oscillatory knitting until one-half the needles are in use, and immediately thereafter commencing the foot portion by circular knitting with the full complement of needles.

4. In the manufacture of seamless hosiery, 35 the process of producing the heel pocket by

commencing oscillatory knitting on approximately one-eleventh part numerically of the entire series of needles, gradually increasing 40 the latitude of said oscillatory knitting until one-half the needles are in use, and immediately thereafter commencing the foot portion by circular knitting with the full series of needles.

5. In the manufacture of seamless hosiery, 45 the method of producing an integral heel pocket in its entirety by widening only in continuation from the leg portion to a region adjoining the instep.

6. In the manufacture of seamless hosiery, 50 the method of producing a complete integral heel pocket by widening only with resultant formation of sutures at the juncture of the heel with the leg portion of the stocking.

7. A seamless stocking characterized by 55 a widened heel pocket having the fashioning sutures without its area.

8. A seamless stocking having a heel pocket 60 formed by widening only characterized by fashioning sutures coincident with the longitudinal median lines at opposite sides of said stocking or juncture between the heel and leg portion.

9. A seamless stocking having a fashioned 65 heel pocket formed by widening only characterized by sutures at opposite sides thereof lying in the line of juncture between the heel and the ankle.

In testimony whereof, I have hereunto 70 signed my name at Philadelphia, Pennsylvania, this 17th day of June, 1921.

EMIL A. HIRNER.
